UNITED STATES PATENT OFFICE.

WILLIAM H. REDINGTON, OF EVANSTON, ILLINOIS.

PASTE-CUP AND SIMILAR VESSEL.

1,110,646.

Specification of Letters Patent. Patented Sept. 15, 1912.

Application filed October 16, 1913. Serial No. 765,419.

To all whom it may concern:

Be it known that I, WILLIAM H. REDINGTON, a citizen of the United States, residing at Evanston, in the county of Cook and State of Illinois, have invented certain new and useful Improvements in Paste-Cups and Similar Vessels, of which the following is a specification.

This invention relates to improvements in paste cups and similar vessels, and its object is to improve the seal to the cover in the vessel.

The invention consists substantially in the construction set forth in the specification, illustrated in the drawing, and more particularly pointed out in the claim.

Like letters refer to the same parts in the several figures of the drawing, in which—

Figure 1 is a side elevation of the complete device; and Fig. 2 is a vertical section of the same.

A designates the main body of the vessel made of any suitable material and preferably of glass.

B designates the cover made of metal, which in the present instance is provided with a dome C for containing and guiding the handle of the brush E.

F is a thread formed on the metallic cover to engage a corresponding thread on the top of the vessel.

G is a packing ring.

H is the paste or other substance contained in the vessel.

It has been found in practice that it is necessary to hermetically seal a paste cup or similar vessel until it is ready for use, for sometimes these paste cups must be transported for long distances, and again they remain on the shelves for an extended period before being used. It has been customary to attach a metallic cover to the glass vessel by a screw thread in the vertical flanges of the cover and to then screw the cover firmly down upon the packing ring on the top edge of the vessel, but it has been found in practice that when these vessels are made of glass or similar material it often happens that there are "fire-cracks" on the top of the neck or vessel or other imperfections and that for this reason it is impossible to get a perfect joint at this point. On the other hand, such imperfections are less inclined to occur at the shoulder of the neck below the thread

on the vessel and consequently a more perfect seal may be made by providing a shoulder on the outside of the vessel just below the thread and flaring outwardly the flange 60 of the cover just below the thread so as to give an approximately flat surface when the packing ring is inserted at this point, as shown in Fig. 2 of the drawing. To this end the screw neck may be made slightly 65 longer than the cover so as to provide a space for the flexible ring, which latter rests on this shoulder. The cover is then screwed down until the flaring flattened lower end of the same bears on the flexible 70 ring and thereby makes a tight joint and hermetically seals the vessel. As before stated, this seal is particularly necessary before the vessel is put into use either during transportation or while it remains on 75 the shelves of the store, and after such use has begun the ring may, if desired, be thrown away and the cover screwed down tightly on the top of the vessel, which will ordinarily be found to form sufficient contact to make an efficient closure during the period the vessel remains in use.

It will be understood, of course, that when the cover is thus screwed down tightly upon the top edge of the vessel a packing 80 washer on the inside of the cover contacts with the edge of the vessel and makes the seal at that point. The screw, of course, is made of such a length as to enable it to cause the lower edge of the circumferential 85 flange to contact with the lower packing ring at the time required, as above stated, or to carry the cover down further when the lower packing ring is omitted so as to produce a contact between the packing ring 90 on the inside horizontal part of the cover and the upper edge of the neck after the purchaser of the device has commenced its use. This upper packing ring is designated by the letter I on the drawing. 100

It will, of course, be understood, that modifications may be made in the above described construction without departing from the principle of the invention.

What I desire to claim and secure by Letters Patent, is:

A cup for paste or like substance comprising a body of vitreous material having a neck formed with a thread and a shoulder below such thread, in combination with a 110 metallic cover having a horizontal surface extending over the neck and a vertical

flange provided with screw-threads to engage the threads on the neck and depending a vertical distance about equal to the vertical height of the neck, a lower packing ring resting on the shoulder and an upper packing ring between the top surface of the neck and the inner horizontal surface of the cover whereby when the edge of such flange engages the lower packing ring the upper packing is not sealed on the surface of the neck but when the lower packing ring is removed and the cover screwed down to

its full extent the upper packing ring is compressed upon the upper surface of the neck and thereby produces a seal at that point. 15

In testimony whereof I have signed my name to this specification, in the presence of two subscribing witnesses, on this 11th day of October, A. D. 1913.

WILLIAM H. REDINGTON.
